UNITED STATES PATENT OFFICE.

EZRA E. REED, OF TOWER, WYOMING, ASSIGNOR OF ONE-HALF TO BERTRAM C. NOBLE,
OF SUNDANCE, WYOMING.

STIRRUP.

1,044,419.

Specification of Letters Patent.

Patented Nov. 12, 1912.

Application filed November 18, 1911. Serial No. 661,025.

To all whom it may concern:

Be it known that I, EZRA E. REED, a citizen of the United States, residing at Tower, in the county of Cook and State of Wyoming, have invented new and useful Improvements in Stirrups, of which the following is a specification.

An object of the invention is to provide a stirrup for preventing injury to a rider 10 when removing the feet from engagement with the stirrup.

The invention embodies a plurality of connectible sections, one of the said sections being adapted for connection with the usual 15 stirrup strap and the other section being mounted on the first-mentioned section so that the second-mentioned section can be removed from interlocking engagement with the first-mentioned section by exerting an 20 upward forward pressure on the lower part of the second-mentioned section.

Reference is to be had to the accompanying drawings constituting a part of this 25 specification, in which similar characters of reference denote corresponding parts in all the views, and in which—

Figure 1 is a perspective view looking at my device from the rear. Fig. 2 is a side elevation showing the lower section partly 30 removed from the upper section. Fig. 3 is a horizontal sectional view, taken on the line 3—3 in Fig. 1. Fig. 4 is a fragmentary perspective view looking at the inner side of the upper section. Fig. 5 is a fragmentary perspective view of the lower section. 35

Referring more particularly to the views, I provide an upper section 10 and a lower section 11, the upper section 10 being adapted 40 for engagement with a stirrup strap 12 and constituting a strap section and the lower section 11 being substantially U-shaped to receive the foot and constituting a stirrup section. Formed on the strap section by cutting away portions thereof, are 45 locking flanges 13 and formed on the stirrup section are guide lugs 14, the locking flanges 13 being adapted to engage flattened edges 15 of the stirrup section, recesses 16 being provided in the stirrup section to receive 50 the guide lugs 14. Rigidly secured to the strap section and depending therefrom are bars 17 having their lower ends provided with cut out portions 18, the said bars being adapted for pivotal engagement with 55 pins 19 formed on the stirrup section, the

said pins being received in the cut out portions 18. Mounted on pins 20 on the strap section are springs 21 having their free ends thereof adapted to slidably engage retaining pins 22 formed on the stirrup section. 60 Formed with the sides of the stirrup section are guide plates 23 arranged to aid in positioning the guide lugs 14 in the recesses 16. A brace rod 24 is secured to the strap section to retain the sides thereof 65 in spaced relation and a similar brace rod 25 is secured to the stirrup section for the same purpose, the said brace rods, when the stirrup section is mounted on the strap section, being in close proximity as shown 70 in Fig. 1. Now, assuming that the stirrup is arranged as shown in Fig. 1, when a horse falls or throws the rider, the mentioned rider in falling from the horse exerts an upward forward pressure on the lower part 75 of the stirrup section, thus causing the stirrup section to swing on the lower ends of the bars 17, having the pins 19 engaged therewith and the mentioned swinging movement of the stirrup section disengages 80 the locking flanges 13 from the flattened edges 15, while at the same time the guide lugs 14 will be moved outwardly from the recesses 16 and as the springs 21 slide relatively to the retaining pins 22, the swinging 85 action of the stirrup section against the action of the springs 21 will cause the free ends of the springs to slide upwardly on the pins 22 and become disengaged therewith, thus entirely releasing the stirrup section 90 from the strap section and preventing the foot of the rider, inserted in the stirrup section, from being wrenched or broken. To reengage the stirrup section with the strap section, the bars 17 are engaged by 95 the pins 19, which are received in the cut out portions 18, the guide lugs 14 are guided by the plates 23, into the recesses 16 so that the locking flanges 13 will repose upon the flattened edges 15 and the free ends of the 100 springs 21 are then passed behind the retaining pins 22, the said springs when in this position being adapted to retain the stirrup section in engagement with the strap section, while the guide lugs 14, in the recesses 16, will prevent the stirrup section 105 from moving gravitationally away from the strap section.

I claim:—

1. A stirrup comprising a strap section, 110

- bars secured to the strap section and depending therefrom, a stirrup section, pins formed on the stirrup section and adapted for pivotal engagement with the said bars,
5 guide lugs formed on the said stirrup section and adapted to extend into recesses in the said strap section, locking flanges formed on the strap section and adapted to be engaged by the stirrup section, and springs
10 mounted on the strap section and slidably engaging the stirrup section to retain the stirrup section in releasable engagement with the strap section.

2. In a stirrup, the combination with a
15 strap section, of a stirrup section for re-

leasable connection therewith, bars on the said strap section, pins on the said stirrup section and pivotally engaged by the said bars, locking flanges formed on the said strap section and normally engaged by the 20 said stirrup section, and springs mounted on the said strap section to slidably engage the said stirrup section.

In testimony whereof I affix my signature in presence of two witnesses.

EZRA E. REED.
